DESIGN FOR A SPECTACLE GUARD

Morris B. Roth, Chicago, Ill.

Application October 26, 1942, Serial No. 108,617

Term of patent 14 years

To all whom it may concern:

Be it known that I, Morris B. Roth, a citizen of Germany, residing at Chicago, in the county of Cook and State of Illinois, have invented a new, original, and ornamental Design for a Spectacle Guard, of which the following is a specification, reference being had to the accompanying drawing, forming a part thereof, in which:

Fig. 1 is a perspective view of the spectacle guard, showing my new design.

Fig. 2 is a top plan view thereof.

Fig. 3 is a side elevational view thereof.

Fig. 4 is an end view thereof.

I claim:

The ornamental design for a spectacle guard, substantially as shown.

MORRIS B. ROTH.
